UNITED STATES PATENT OFFICE.

FRANK J. BOEHLER, OF KALAMAZOO, MICHIGAN.

WEATHER STRIP.

Application filed December 2, 1925. Serial No. 72,799.

This invention aims to provide novel means for mounting a weather strip on the lower portion of a door, and for moving the weather strip downwardly, to cooperate with the threshold, when the door is closed.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in elevation, a device constructed in accordance with the invention, assembled with the door;

Figure 2 is an elevation showing the inner surface of the support and attendant parts;

Figure 3 is a section on the line 3-3 of Figure 2;

Figure 4 is a section on the line 4-4 of Figure 1;

Figure 5 is a detail enlarged from Figure 2.

The numeral 1 marks a frame, such as a door frame, whereunto a closure or door 2 is hinged at 3 for horizontal swinging movement, the threshold being marked by the numeral 30.

The device forming the subject matter of this application includes a support 4, in the form of a strip, held by securing elements 5 on the door 2 at the lower end thereof. A packing ribbon 6, which may be made of rubber, is let into the inner side of the support 4 at the upper edge thereof, and, cooperating with the door 2, affords a tight closure which prevents water from finding its way downwardly between the support 4 and the door 2. At its inner surface, the support 4 has a longitudinal groove 7 which opens at one end through the support 4. Loop-shaped bearings 8 are mounted in the groove 7 and have oppositely extended wings 9 secured at 10 to the support 4, and overlapped on the inner surface of the support, as clearly shown in the drawings.

A plunger 11 is mounted for right-line

reciprocation in the bearings 8, and the bearings extend about the plunger 11 far enough to hold the plunger in place. An adjustable head 12, such as a nut, is mounted on the outer end of the plunger 11 and is located in the groove. A compression spring 14 surrounds a portion of the plunger 11, one end of the spring 14 abutting against the head 12 and the other end of the spring abutting against one of the bearings 8, within the groove 7. An adjustable operating member 15, such as a screw, is threaded into one vertical portion of the door frame 1 and is adapted to engage the outer end of the plunger 11, when the door 2 is closed. In the lower edge of the support 4 there is a recess 16. A weather-strip 17 is mounted for vertical sliding movement in the recess 16 and is supplied at its lower end with a lip 18, preferably made of felt, and adapted to cooperate with the threshold 30, if a threshold is used. There are notches 19 in the inner surface of the support 4. The notches 19 communicate with the recess 16 and with the longitudinal groove 7. In the notches 19 are located bell crank levers 20 including longitudinally extended arms, and transverse arms. The bell crank levers 20 are fulcrumed at 21 on the support. The transverse upstanding arms of the bell crank levers 20 are pivoted at 22 to the plunger 11. The longitudinal arms of the bell crank levers 20 are pivoted at 23 to the upper ends of upstanding arms 24 secured to the weather strip 17.

If desired, the door frame 1 may carry weather strips 25 adapted to cooperate with the door 2, about its entire periphery, excepting the bottom of the door. The weather strips 25, in addition to the mechanism shown in Figure 2, close the space entirely about the door, and prevent the entrance of air.

When the door 2 is closed, the operating member or screw 15 engages the end of the plunger 11 and moves the plunger to the right in Figure 2. When the plunger moves to the right, the bell crank levers 20 are operated, and lower the other strip 17 into engagement with the threshold 30. The operating member or screw 15 may be threaded inwardly and outwardly in the door frame 1, so as to cooperate properly with the plunger 11 and thereby to cause the weather strip 17 to be lowered the desired amount, when the door is closed.

When the door is opened, the spring 14 reacts, and raises the weather strip 17, by means of the plunger 11 and the bell crank levers 20, until the upper edge of the weather strip 17 abuts against the support 4, at the upper end of the recess 16.

What is claimed is:—

A device of the class described, comprising a support which is provided with a longitudinally extended groove, bell cranks fulcrumed intermediate their ends on the support, loop shaped bearings in the groove, a rod slidable in the bearings in spaced relation to the walls of the groove, a compression spring through which the rod extends, the spring abutting against one of the bearings, a weather strip mounted to slide on the support, the bell cranks being

pivoted to the weather strip and to the rod, an adjusting nut threaded to move along the rod and engaging the spring to adjust the pressure of the spring against the said bearings, the bearings being supplied with oppositely extended wings which are secured to the support on opposite sides of the groove, the bell cranks forming the sole connecting means between the weather strip and the rod, and the nut being independent of said means, the bearings being restricted at their outer sides, to hold the rod for sliding movement in the bearings.

In testimony that I claim the foregoing as my own, I have hereto affixed my signature.

FRANK J. BOEHLER.
